UNITED STATES PATENT OFFICE.

JAMES CONNIEF, OF OCONTO, WISCONSIN.

VEHICLE-AXLE.

SPECIFICATION forming part of Letters Patent No. 224,077, dated February 3, 1880.

Application filed July 9, 1879.

To all whom it may concern:

Be it known that I, JAMES CONNIEF, of Oconto, in the county of Oconto and State of Wisconsin, have invented a new and Improved Vehicle-Axle, of which the following is a specification.

The object of this invention is to reduce the friction between the axle and the spindles when the latter revolve with a fixed wheel.

10 It consists of an axle made of cast-iron in a cylindrical form, and divided off at each end into compartments, in which are placed rollers in a circle, so as to form a bearing for the spindles which are inserted in the ends of the axle. The spindles are held in the axle by collars, which rest in one of the compartments between balls, which hold them steadily and prevent endwise motion without producing much friction.

20 In the accompanying drawings, Figure 1 is a longitudinal section of my improved axle with spindles of different construction inserted. Fig. 2 represents the same in elevation; and Fig. 3 is a cross-section of the axle and spindle on line $x-x$, Fig. 1.

25 Similar letters of reference indicate corresponding parts.

Referring to the drawings, A represents the cylindrical axle, having midway of its length a socket, a, for the end of the reach, and a hole for the king-bolt. On the back of the axle is a semicircular support, b, for the reach, and in front are hounds c, c, between which is pivoted the end of the tongue or pole. On either side of the socket a the axle is divided into compartments d d' d'' by partitions e. In compartments d d'' are placed rollers f, arranged in a circle, so as to leave a central space, and in d' are placed balls g.

30 B B' are the spindles. The first is a straight shaft with iron hubs h h, while the latter, being adapted for wooden hubs, has a square projection or end for inserting in the hub, while the portion i, extending through the first compartment next to the end of the axle, has an enlarged diameter.

On the spindle are collars C. The spindles are inserted in the axle in the space between the rollers f, as shown clearly in Fig. 3, so that the two parts of it on either side of the collar 50 bear upon the rollers in the compartments d d'' , while the collars C are held in compartments d' between balls g, as clearly shown.

By this arrangement the friction between 55 the spindles and their bearings in the axle is greatly reduced, as the rollers revolve on their axis at the same time with the spindle, and with this advantage the axle possesses great strength, and in case of the breaking of a 60 spindle it can be removed without trouble or expense and another inserted in place of it.

The collars C, held in compartments d' between balls g, securely connect the spindles with the axle and prevent endwise motion of 65 the spindles. At the same time undue friction is avoided, as the collars revolve the balls on their axis whereby the rubbing of the collars is overcome.

Having thus described my invention, what 70 I claim as new, and desire to secure by Letters Patent, is—

As an improvement in vehicle-axes, the cylindrical metal axle A, with socket a and support b for the reach, and provided with compartments d d'' , with rollers f therein, and intermediate compartment, d' , with balls g therein, in combination with the spindles provided with collars C, inserted in the axle so as to bear on the rollers f, while the collars C are held 75 in the compartment d' between rollers g, whereby the spindles are securely connected with the axle, the friction is greatly reduced, and endwise motion prevented, substantially 80 as described.

JAMES CONNIEF.
